JULIUS WINTER, OF NEW YORK, N. Y.

CARBURETOR.

1,414,935.

Specification of Letters Patent.

Patented May 2, 1922.

Application filed January 8, 1919. Serial No. 269,437.

To all whom it may concern:

Be it known that we, (1) JOHN J. COX and (2) RICHARD WENDELKEN, citizens of the United States, residing at (1) New York, in the county of New York, (2) New York, in the county of Bronx, and State of New York, have invented new and useful Improvements in Carburetors, of which the following is a specification.

10 This invention relates to carburetors for internal combustion engines, and more particularly to carburetors of the general type shown and described in the application for Letters Patent filed by Richard Wendelken 15 August 12, 1918, Serial No. 249,534, a carburetor of this type comprising a body composed of a small number of connected parts of such simple configuration that they may be readily formed of suitable material by 20 means of dies, and said carburetor comprising capillary elements for delivering the liquid hydrocarbon from the reservoir to the air to form the combustible mixture, said elements cooperating with a fuel feeding 25 member in such a manner that the quantity of hydrocarbon supplied is controlled by the extent of opening of said valve.

The invention has for its objects to provide a carburetor body of improved and 30 simplified form; to provide a novel combined valve and fuel supply mechanism capable of performing its intended function in an efficient manner, and which may be readily and conveniently adjusted in accordance with the requirements; and to provide 35 a new and improved capillary element for use in carburetors of this character, said capillary element being of durable construction and capable of withstanding the wear 40 to which it is subjected in use, and being reliable in its operation and of delicate adjustability.

The foregoing and other objects of the invention, together with means whereby the 45 same may be carried into effect, will best be understood from the following description of certain forms or embodiments thereof illustrated in the accompanying drawings. It will be understood, however, that the particular constructions described and shown 50 have been chosen for illustrative purposes, merely, and that the invention, as defined by the claims hereunto appended, may be otherwise practiced without departing from 55 the spirit and scope thereof.

In said drawings:

Fig. 1 is a vertical section, taken substantially on the line 1—1, Figs. 2 and 4, of a carburetor constructed in accordance with the invention.

Fig. 2 is a fragmentary view of the mechanism associated with one of the capillary elements.

Fig. 3 is a similar view showing another form of capillary element.

Figs. 4, 5, and 6 are respectively a vertical section, plan and end elevational views, respectively, showing a modified construction.

Fig. 7 is a side elevation, partly broken away, of the upper part of the carburetor 70 shown in Fig. 4.

Fig. 8 is a detail view of the capillary element shown in Fig. 2.

Fig. 9 is a detail longitudinal section, and Fig. 10 is a detail side elevation, of the capillary element shown in Fig. 3.

Fig. 11 is a detail fragmentary plan view and Fig. 12 is a detail fragmentary vertical sectional view showing the carburetor equipped with a modified form of capillary element.

Fig. 13 is a detail elevation and Fig. 14 is a bottom plan of the capillary element shown in Figs. 10 and 11.

Fig. 15 is a detail sectional view and Fig. 16 is a detail plan view to a somewhat enlarged scale of the fuel feeding member which carries the aforesaid modified capillary element.

Fig. 17 is a detail elevation and Fig. 18 is a detail plan view of a further modified construction of the capillary element.

Referring to Fig. 1, the body of the carburetor comprises a main or lower section 20 and a superimposed top section 21, said sections being secured together by means of bolts or screws 22 which pass through apertured ears or lugs 23 formed on the two sections. The lower section 20 comprises a fuel reservoir 24, the upper section 21 is provided with an air inlet 25, while the two sections are formed at their adjacent faces with complementary concavities collectively constituting a horizontally disposed combined air passage and mixing chamber 26. The fuel reservoir 24 is provided with the usual drain cock 27 and is supplied with fuel through a suitable inlet pipe 28, the liquid level in said reservoir being controlled by a valve 29 operated by a float 30. The

float valve may be of any suitable construction, but as herein shown is of the type more fully described in the prior application above referred to. The passage 26 communicates at one end with the air inlet 25, while its opposite end constitutes an outlet 31 adapted to communicate with the engine manifold, said outlet being provided with a vertically disposed coupling flange 32 comprising complementary portions formed on the body sections 20 and 21, respectively. The fuel reservoir or float chamber 24 is separated from the passage 26 by a plate 33 seated at the upper edge of said reservoir or chamber and retained in position by means of rods 34 carried by said plate, their upper ends engaging the top section 21.

It will be observed that each of the body sections is of relatively simple shape, having no closed recesses or overhanging portions tending to interfere with its formation by means of dies, which need not be at all complicated. The complete body may accordingly be readily produced by the die process, and may, therefore, conveniently be composed of plastic material, or, preferably, of any one of that class of condensation products or compositions which are caused to solidify, from a powder, in any desired shape, under the pressure of heated forming dies, and variously known in the arts as "bake-lite", "condensite", etc. Certain of these substances, particularly "bakeelite", have been found to possess marked and special advantages for use in the manufacture of carburetors. When formed of such a material, the various attaching portions of the body sections may have embedded therein suitable bushings, thimbles, or the like, 35.

40 The top body section 21 is provided with a vertical groove or channel 36 communicating with the passage 26 and in which is guided, for movement in a direction transverse to the passage 26, a reciprocating fuel feeding member 37. The fuel feeding member 37 is normally held in its lowermost or closed position, as shown in dotted lines in Fig. 1, by means of capillary elements or members (hereinafter more fully described), generically indicated by the numeral 38, secured at their upper ends to a flange 39 extending laterally from the bottom of said fuel feeding member, said members passing downwardly through openings in the plate 33 and carrying at their lower ends disks 40 between which and the plate 33 are interposed springs 41. The fuel feeding member 37 may be raised to any desired extent against the tension of the springs 41 by 45 means of a flexible cord or wire 42 (preferably a twisted or braided wire cord) secured at its lower end to said fuel feeding member, passing upwardly through a suitably disposed opening in the top body section 21, and secured at its upper end to an

operating drum or segment 43 having an operating lever 44 and pivoted to an angular bracket 45 secured, as by screws 46, to the top body section. The capillary elements 38 may be of any suitable number, three being shown in Fig. 3.

Interposed between the air inlet 25 and the fuel feeding member 37 is an air valve 47 comprising a flat plate provided with trunnions 48 which are received in mating 75 sockets or recesses formed in the adjacent edges of the body sections 20 and 21. The valve 47 is normally held in the vertical position shown in dotted lines in Fig. 1, to close the passage 26, by means of a spring 80 pressed plunger 49 which engages a lip 50 on said valve. The plunger 49 is slidably mounted in a sleeve or tube 51, retained in suitably disposed openings in the body section 21, and is pressed against the valve lip 85 50 by a spring 52 interposed between the head of said plunger and an adjusting screw 54 in the outer end of said tube. The adjusting screw 54 is provided with an operating head 55, and may be yieldingly retained in adjusted position by means of a plunger 56 having a conical or pointed head 90 cooperating with a series of suitably disposed recesses in the head 55, said plunger 56 being slidably mounted in a bushing or tube 57 supported in the body section 20, and being pressed into engagement with said head by a spring 58.

For the lower range of running speeds, the air valve 47 is opened, to a greater or less extent, by the air pressure in the passage 26 induced by the suction of the engine. Throughout the higher range of speeds, however, said valve 47 is positively operated by and in correlation with the fuel feeding member 37. To this end the fuel feeding member 37 is provided with one or more (herein two) rearwardly extending arms or fingers 59 adapted, as said fuel feeding member 37 is raised, to engage the edge 100 of the partially open valve 47 and fully open the same, as shown in full lines in Fig. 1. It will be observed that, at low running speed, the air valve is out of the path of movement of the fingers 59.

115 In priming, it is necessary to hold the air valve 47 closed against the suction of the engine in order that a charge rich in fuel may be drawn into the engine cylinders. To this end there is provided a locking lever 60 pivoted to a lug or ear 61 formed on the body section 21, said lever having a finger 62 adapted to pass through a suitably disposed opening in the body section 20 and occupy a position in advance of the valve 120 47, when the latter is closed, and prevent the same from opening. The lever 60 is normally held with its finger 62 in inoperative position out of the path of movement of the valve 47.

It is a common fault in carburetors, especially when operated on lean mixtures to cause stalling of the engine when the throttle is suddenly opened, due in part to the sudden 5 relief of vacuum in the engine cylinders which causes a falling off in the velocity of the air past the fuel feeding element. This decreases the proportion of fuel constituent picked up by the air, impoverishing the 10 mixture to a point at which the engine will not operate. To obviate this defect the outlet 31 for combustible mixture is provided with a disk valve 64 provided with trunnions 65 mounted in sockets or recesses in the 15 body sections in the same manner as the trunnions 48 of the air valve 47. The outlet valve 64 is also positively operated by and in correlation with the fuel feeding member 37, and to this end is provided 20 with an arm 66 connected by a link 67 with an extension 68 on the flange 39 of said fuel valve.

The rate of opening of the passage uncovered by said outlet valve will follow 25 more or less closely the sine curve and will lag behind the rate of presentation of the fuel feeding elements which are controlled by the reciprocating fuel feeding member. This enables the mixture to be enriched 30 ahead of the relief of the vacuum in the engine cylinders.

In order to provide for an additional air supply when the valve 47 is fully open and the quantity of air drawn through the passage 26 from the inlet 25 is insufficient, there is provided an auxiliary air valve 69 located in a chamber 70 in the top body section immediately below the bracket 45. The chamber 70 communicates with the passage 40 26 through a port 71 and with the external atmosphere through ports 72 in the base of the bracket 45. The valve 69 is held normally seated, to close communication between the ports 72 and 71, by means of a 45 spring 73 interposed between said valve and the base of said bracket, and is provided with a stem 74 which extends downwardly into the path of movement of the flange 39 of the fuel feeding member 37. 50 When said fuel feeding member approaches the limit of its opening movement, the stem 74 is engaged by the flange 39, the valve 69 is unseated, and an additional supply of air is allowed to enter the passage 26, beyond the fuel valve, through the ports 72, 55 chamber 70, and port 71.

In apparatus of this general character as usually constructed it has heretofore been customary to employ, for the capillary elements, absorbent members in the form of wicks or the like composed of textile or similar material. An important object of the present invention is to provide an improved form of capillary element or member 60 for use in carburetors of this type, which element or member will be strong and durable so as not to be subject to breakage or excessive wear under the conditions of use, and which will, at the same time, perform its intended function of supplying an accurately graduated quantity of fuel in a reliable and efficient manner. To these ends the invention contemplates the provision of a capillary member which may be composed of a hard, strong, durable material, such as 75 metal. Thus, as shown in Figs. 2 and 8, the capillary element or member 75 comprises a wire cord composed of a plurality of twisted, woven, or braided strands of fine metallic wire. Preferably, however, and as shown in 80 Figs. 6, 12, and 10, the member or element 76 comprises a capillary tube having an open lower end 77 to communicate with the fuel in the reservoir 24, and which may be upset or flanged to retain the washer 40, 85 as shown in Fig. 3, and with a threaded upper end 78 to engage the flange 39 of the feeding member 37 or a washer 79 superimposed thereon. Adjacent its upper end the tube 76 is provided with a series of 90 graduated openings 80, said openings being of progressively increasing diameter from the upper to the lower end of the series, whereby as said tube is raised by the fuel feeding member 37, as above explained, 95 openings of successively greater size will be exposed above the plate 33 to supply a progressively increasing quantity of fuel. The openings in the plate 33 through which the capillary members pass are preferably provided with downwardly depending flanges, the flange 81 shown in Fig. 5 loosely surrounding the member 75 in order to avoid discharging the liquid fuel carried thereby, but the flange 82 shown in Fig. 3 engaging the tube 76 (which carries the fuel entirely in its interior bore) with a close sliding fit, thereby closing communication between the fuel reservoir 24 and the passage 26, and covering such of the openings 80 as 100 are below the top of the plate 33.

In addition to the springs 41, acting through the capillary members to depress the fuel feeding member 37, there may be provided springs 95 housed in tubular casings 96 carried by the top body section 21, said springs engaging at their upper ends the closed outer end of said casings and at their lower ends the upper edge of the fuel feeding member 37 adjacent the ends 115 of the latter. The springs 95 assist the springs 41, which may be made correspondingly lighter, thereby reducing the strain upon the capillary members. In fact, if the springs 95 be employed, the springs 41 may 120 be dispensed with altogether, particularly if the rigid capillary tubes 76 be used, although said springs 41 will preferably be retained with the flexible capillary members 75 in order to hold them taut. 125

The carburetor shown in Figs. 4 to 7 is substantially similar to that shown in Figs. 1 to 4 as to its essential features, which, therefore, do not require description in detail. In this form of the invention, however, the combined air passage and mixing chamber 83 is formed principally in the lower body section 84, while the upper body section 85 forms a closure for the top of said passage or chamber and is provided with an air inlet 25, as in the construction first described, and with an upwardly directed outlet 86 provided with a horizontally disposed attaching flange 87, the outlet valve 88 being correspondingly disposed in said outlet. Also in this construction the auxiliary air valve 89 is located in a casing 90 carried by the top body section 85, and controls a port or passage 91 leading to the outlet 86, said valve having a stem 92 which is engaged by the main air valve 47 when the latter is fully opened to open said valve 89. The valve 89 is normally held to its seat by a spring 93 interposed between said valve and the cover 94 of the casing 90, said cover having perforations through which atmospheric air enters said casing.

Figures 11 to 16 illustrate a modification of the construction of the capillary element according to which the said element is in the form of a rigid bar being connected to the fuel feeding member 37 similarly to the capillary element 76 of Figures 9 and 35 10 and is provided with a plurality of capillary grooves 96 extending from its lower end and having their upper ends at different elevations. It is manifest that in this construction as the bar is raised the upper ends of the grooves 96 will be exposed in the passage 26 in progressively increasing number. With this modified form of capillary element, it is preferred to provide the plate 33 with relatively long guide sleeves 40 45 82 through which said element projects.

Figures 17 and 18 illustrate a further modification in the construction of the capillary element. In this modification, the capillary element has the same features as 50 the form shown in Figure 13, but in addition has a central bore which extends from its lower end and terminates at a point well above the upper termination of the longest duct 96, the said bore communicating at 55 its upper end with a transverse discharge duct 97 and serving to supply hydrocarbon

fuel for low speed running when the fuel feeding member 37 is in its lowermost position. It is to be noted that if desired the parts may be arranged whereby the fuel feeding member in its lowermost position as shown in Figure 12 will still leave a relatively small area of communication between the inlet 25 and the discharge opening 31 and that the hydrocarbon fuel for low speed running will be discharged into said area of communication, whether the capillary element be of the form shown in Figure 17 or of the form shown in preceding figures. 70

What is claimed is—

1. A carburetor for internal combustion engines comprising a fuel chamber, a mixing chamber, a valve for controlling the admission of air to the mixing chamber, a reciprocating fuel feeding member in said mixing chamber, a butterfly outlet valve for controlling the flow of combustible mixture to the engine, a plurality of capillary members connected to and movable with said fuel feeding member and extending into said fuel chamber, the area of which members exposed in said mixing chamber varies in accordance with the position of said fuel feeding member, connections between said fuel feeding member and butterfly outlet valve and co-acting parts on said fuel feeding member and air valve whereby said butterfly outlet valve and air valve may be operated by the fuel valve. 90

2. In a carburetor the combination with a mixing chamber of a reciprocating fuel feeding member therein and a butterfly outlet valve for said chamber operated by said fuel feeding member. 95

3. A carburetor comprising a fuel chamber, an air inlet passage, a mixing chamber, a reciprocating fuel feeding member therein, a butterfly outlet valve for said mixing chamber, means connected with said fuel feeding member for operating said butterfly outlet valve and one or more capillary members carried by said fuel feeding member extending into said fuel chamber. 100

In testimony whereof we have hereunto set our hand in presence of two subscribing witnesses.
